UNITED STATES PATENT OFFICE.

ARTHUR LANGERFELD, OF NEW BRITAIN, CONNECTICUT, ASSIGNOR TO
P. & F. CORBIN, OF SAME PLACE.

DESIGN FOR ORNAMENTATION OF BUILDERS' HARDWARE.

SPECIFICATION forming part of Design No. 14,888, dated March 18, 1884.

Application filed December 8, 1883. Term of patent 14 years.

To all whom it may concern:

Be it known that I, ARTHUR LANGERFELD, a citizen of the United States, residing in New Britain, in the county of Hartford and State 5 of Connecticut, have invented and produced a new and original Design for Ornamenting Articles of Hardware, of which the following, taken in connection with the drawings heretofore filed, and the letters of reference marked 10 thereon, is a full, clear, and exact description of the same.

Figure 1 is a flat view of an escutcheon which is ornamented with my design. Fig. 2 is a section of the same on the line A B, these 15 two views being deemed necessary to fully illustrate my design.

The leading features of my design are the high ornamental borders C and D D², the low space E E² E³, filled with scales, the dotted 20 spaces F F², the latticed groundwork of the dotted spaces F F², and the composition of all or any of these features inclosed or bordered by a flush raised band, G.

The border C consists of an alternating 25 succession of raised plain circles and raised plain narrow figures with hollowed sides and straight ends, and a narrow sunken space or line C, Fig. 2, on each side of this succession.

The borders D D² consist of an alternating 30 succession of raised flat diamonds and circles, which are connected so that only two angles of the diamond remain. In each diamond is a sunken dot, D², Fig. 2, and within each circle is a large raised plain circle, D, Fig. 2, and on 35 each side of this succession is a narrow raised

stripe. All the raised parts are flush with each other.

The ground E E² E³ consists of scales so formed as to have the appearance of successively growing out from under each other, as shown 40 in the section, Fig. 2, at E. The scales are arranged in straight rows, as at E E², Fig. 1, or curved rows, as at E³, and have rounded ends. This groundwork of scales is inclosed by a raised band, H, whenever it is not bordered by other raised work, as the groundwork E and E³ is. 45

The groundwork or spaces F F² consist of a ground upon which raised dots I are distributed. These dots may represent the heads 50 of nails, screws, or rivets, and may be shaped round, square, or in any other form. The groundwork of the dotted spaces F F² is further described as consisting of an even ground upon which a diagonally-placed lattice-work 55 is formed, as shown in the section, Fig. 2, at I.

All the raised parts of this design are flush with each other.

I claim—

The design for an escutcheon or other article of hardware, consisting of the ornamentation C and D, the borders G, the groundwork E, decorated with scales, and the groundwork F, decorated with dots and lattice-work, as described and shown. 65

ARTHUR LANGERFELD.
